UNITED STATES PATENT OFFICE

102,304

DESIGN FOR A BUILDING

Robert E. Pellow, Waco, Tex.

Application June 30, 1936, Serial No. 63,586

Term of patent 14 years

To all whom it may concern:

Be it known that I, Robert E. Pellow, a citizen of the United States of America, residing at Waco, county of McLennan, and State of Texas, have invented a new, original, and ornamental Design for a Building, of which the following is a specification, reference being had to the accompanying drawing, wherein:

I claim:

The ornamental design for a building, as shown.

ROBERT E. PELLOW.
